(57) **CLAIM**

We claim the ornamental design for a single-cup brewer and mat combined, as shown and described.

DESCRIPTION

FIG. 1 is a perspective view of our new design for the combination of a single-cup brewer and a mat in an assembled state with a top surface of the mat abutting a bottom surface of the single-cup brewer;

FIG. 2 is a perspective view of the single-cup brewer and the mat in an exploded state with the top surface of the mat located away from the bottom surface of the single-cup brewer;

FIG. 3 is a front, rear, and/or side view elevation of the single-cup brewer and the mat, excluding the broken lines; FIG. 4 is a bottom view of the single-cup brewer and the mat in an assembled state with the top surface of the mat abutting the bottom surface of the single-cup brewer;

FIG. 5 is a perspective view of the single-cup brewer shown separately from the mat to allow for additional clarity in the showing of the component;

FIG. 6 is a top view of the single-cup brewer;

FIG. 7 is a typical side view elevation of the single-cup brewer, excluding the broken lines. The side view is the same at any point around the periphery of the article;

FIG. 8 is a cross-sectional view of the single-cup brewer taken along lines 8-8 of the side view elevation of FIG. 7; and,

FIG. 9 is a bottom view of the single-cup brewer;

FIG. 10 is a perspective view of the mat shown separately from the single-cup brewer to allow for additional clarity in the showing of the component;

FIG. 11 is a top view of the mat;

FIG. 12 is a bottom view of the mat; and,

FIG. 13 is a side view of the mat as viewed from a point located around the outer circumference of the mat in which one of the four channels formed in the bottom surface of the mat is visible from this point of view, if the mat is rotated 90 or 180 degrees in either the clockwise or counter-clockwise direction then the resulting corresponding side view would be identical to that of FIG. 13, which is due to

(Continued)

the 90 degree spacing of the four channels formed in the bottom surface of the mat as better seen in FIGS. 4 and 12. The dashed broken lines in the drawings illustrate portions of the single-cup brewer and mat combined that form no part of the claimed design. The dash dot broken lines in FIG. 2 illustrate the path along which the components are exploded and in FIG. 7 illustrate the line along which the cross-sectional view is taken. The oblique dashed lines in FIG. 8 illustrate a cross section of transparent material.

1 Claim, 13 Drawing Sheets
